ABSTRACT OF THE DISCLOSURE

An internal combustion engine crank case purging system having means for providing air to the crank case in proportion to engine speed as related to air intake to the cylinders and a vent from the crankcase to the engine air intake through a special tortuous passage which will not significantly interfere with the passage of blowby gases but which has large surface areas capable of or treated in such a manner as to cause adhesion of solids carried by blowby fumes.

Related applications

This application is a continuation-in-part of application Ser. No. 487,221, filed Sept. 14, 1965, now abandoned, which application was copending with application Ser. No. 298,760, filed July 30, 1963, now issued as Patent No. 3,232,284. Another related copending application is application Ser. No. 519,132, filed Jan. 6, 1966, abandoned in favor of continuation-in-part application Ser. No. 700,336, filed Oct. 27, 1967, now issued as Patent No. 3,416,503, describing improvements on the present fume elimination system.

Background of the invention

Field of the invention.—Crankcase fumes, which are a prime cause of air pollution, are to an extent the end product of partially burned, or cracked, fuel and air which is heated and forced past the piston rings by the explosions within the combustion chamber. The removal of these fumes from the crankcase is vital to prevent the corrosion of parts and the deterioration of the lubricating oil of the engine. Various methods have been devised heretofore to remove the fumes. However, in an appraisal of venting systems, which date back many years, it is found that they either had insufficient venting ability at low speeds or that they provided too much ventilation at high speeds. Until quite recently, crankcase fumes were emitted directly into the atmosphere; this practice is now being discontinued. In more recent designs of crankcase ventilating systems, where the fumes are returned to the intake manifold to be burned by the new fuel-air charge, troubles are encountered by the gum and varnish-forming material rendering inoperative the movable control valves. More recent crankcase ventilating systems appear to be temporary expedients with external hose lines from the crankcase. Fumes laden with gums and solid particles as drawn through the hose line from the crankcase, are also inclined to clog filters and to deposit on and change the air flow and fuel metering characteristics of the carburetor venturis.

Crankcase fumes have been found to contain the following harmful materials, namely: (1) water, (2) carbon, (3) gasoline, (4) lead decomposition products, (5) sulphur products (acid forming), (6) resins, and (7) silica. Of these seven different materials, water containing sulphur, and gasoline, are readily burnable with the new charge in the cylinders. It is the solids, e.g., carbon, decomposed lead, resins and silica which should be removed before they are returned to the engine intake.

Summary of the invention

In the present invention I provide an adhesion surface unit with a tortuous passage causing many changes of direction of flow, with the surfaces either treated or 5 coated or otherwise made attractive for adhesion of solid deposits thereon, providing a major contribution to crankcase ventilation. Crankcase ventilation is further enhanced by thoroughly purging the crankcase with air in proportion to engine speed and load; or even increasing the ratio of purging as the speed and load increases. This 10 feature is provided for by a ram-air scoop at the entrance of the air intake of the engine. Thus as the engine inducts more air, more air is scooped from upstream of the venturi, or from any other logical location in the air 15 passage of the engine, to pressurize the crankcase. The ventilating is also increased by increased suction on this air at the outlet of the venturi. Further modifications of the invention include means for reducing the otherwise 20 high suction applied to the passage leading from the crankcase when the throttle valve approaches its closed position as in idling or low power conditions of the engine.

A primary object of the present invention is to eliminate 25 deficiencies in crankcase ventilating systems by providing air to the crankcase substantially proportionate to the engine speed as related to air intake to the cylinders.

Another object of the invention is to control residue 30 deposits in a crankcase ventilating system by providing a removable device having a special tortuous passage and provided with multiple adhesion enhancing surfaces.

A further object of the invention is to improve anti-air 35 pollution aspects of crankcase ventilating systems by providing integral with the engine a ram-like intake purging unit operable to control removal of fumes from various engine areas.

Description of the drawings

These and other objects of the invention will become 40 apparent from the following description and the accompanying drawings, illustrating preferred embodiments of the invention in which like reference characters refer to like parts throughout the several views and in which:

Description of the preferred embodiments

An internal combustion engine 10 is shown as comprising a crankcase structure 12, on top of which is mounted an air intake manifold structure 14. Cylinder head structures 16 are connected to the manifold structure 14, and have port runners 18, through which extend passages 20 for push rods 22 for the operation of rocker arms 24 actuating the valves 26 of the engine. The rocker arms 24 are contained within rocker box covers or housing 28.

An air intake-crankcase breather assembly 30 is mounted on top of the air intake manifold structure 14, as are fuel spray jet assemblies 32 arranged to inject fuel into the port runners 18. An air cleaner assembly 34, mostly omitted for clarity, is mounted on top of the assembly 30, and is preferably arranged to receive ram air for delivery into the assembly 30.

The assembly 30 has a substantially central air intake passage 36 provided with a venturi 38 at its upper end, as shown in FIGURES 3 and 4. Adjacent the venturi and at a point of high velocity of air entering the venturi, is located a scoop type inlet opening 40 for delivery of ram air through port 41A and port 41 into a substantially vertical passage 42 leading downward through the assembly 30 and connecting with a chamber 44 in the air intake manifold structure 14. Some air then passes through a port 46 into the crankcase 12.

Most of the air passes into another chamber 64 provided in the intake manifold structure 14 and openly connected with the chamber 44, to deliver air into a passage 66 in the assembly 30. Pipes 68 are connected with the chamber 64, and deliver the air to the rocker box housings 28, the air then passing downwardly through the push-rod passages 20 into the crankcase, for the purpose of ventilating the area of the rocker arms and valves 26, preventing crankcase fumes and the blowby gases from depositing gum and residue on these parts.

It will be apparent that at higher engine speeds, a greater amount of air is being delivered to the engine; consequently air velocity at the scoop opening 40 will be higher, thus delivering more air to the rocker box housings and crankcase for purging of crankcase blowby fumes. These fumes will rise through ports 48 into a second chamber 50 in the intake manifold structure 14 and then into a second vertical passage 52 in the assembly 30. The passage 52 is openly connected through ports 53 and 53A with the air intake passage 36 of the assembly 30 through an annular port 54 located at a point of low atmospheric pressure just downstream of the venturi 38. As will be apparent there is thus provided a differential in pressure between the inlet opening 40 subjected to higher than atmospheric pressure and the port 54 subjected to lower than atmospheric pressure, causing the crankcase to be positively ventilated, and the fumes to be carried downwardly through the air intake passage 36 into the air intake manifold passage 56 for delivery to the engine cylinders where, with the fuel air mixture, the fumes will be burned. As seen in FIGURES 1 and 2 a third set of ports 58 is provided between the crankcase 12 and the air intake manifold structure 14 to vent fumes between baffles 97 and through ports 97A into a chamber 60 in the intake manifold structure 14, and then into a passage 62 provided in the fuel spray jet assembly 32. The assembly 32 is an air aspirator type of fuel spray jet, but instead of air, the fumes from the crankcase are used for aspiration, which occurs at idling and low engine speeds for the purpose of preventing suction from being applied to the fuel jet and to help in atomization.

The passages 42 and 52 as seen in FIGURES 4, 5 and 6 are provided with substantially similar baffle assemblies 68 and 70 arranged as shown around cores 72 and 74 to form direction changing, somewhat helical passage 76 and 78. The lower ends of the baffle assemblies 68 and 70 extend downwardly into the chambers 44 and 50 of the manifold structures 14, as shown in FIGURE 4, and are

provided in this area with elongated fins 80 and 82 to provide pluralities of substantially or relatively narrow passages having rather large wall surface areas. The lower ends of the baffle assemblies 68 and 70 are provided with laterally extending flanges 84 and 86 arranged to overlie but be spaced from the ports 46 and 48 leading into and from the crankcase. These flanges 84 and 86 are for oil separation and can be of other shapes or form.

At the upper end of the assembly 30, the passages 42 and 52 open into a cover structure 88 which has chambers 90 and 92 provided with baffles 88A and 88B ported respectively through the ports 41A and 54 into the inlet opening 40 and the port 54. When the air cleaner assembly 34 has been removed, the cover structure 88 may be removed by taking out screws 94 and the baffle assemblies 68 and 70 can then be withdrawn readily from their respective passages 42 and 52 for cleaning.

The chamber 60 in the manifold structure 14 is provided with the previously mentioned plurality of baffle elements 97, providing a plurality of relatively small passages having extensive wall surface areas and open through the ports 97A to an upper portion of the chamber 60. The extensive wall surface areas of the baffle assemblies 68 and 70 and the baffle elements 97 also have a chilling effect to act as flame arresters, protecting the crankcase from the possible effects of backfire.

In operation, ram air is forced through the venturi 38 down through the air intake passage 36 into the air intake manifold for delivery through the port runners 18 to the engine cylinders. The ram air also will be forced through the inlet opening 40 into the chamber 90, down through the somewhat helical passage provided by the baffle assembly 68 extending through the vertical passage 42, into the chamber 44 of the intake manifold of the structure 14. A small part of the air passes around the flange 84, through the ports 46, and thence into the crankcase proper. The major portion of the air from the chamber 44 will exit through the side chamber 64 into the passage 66 and the pipes 67 through the rocker box housings 28, then down through the push rod passages 20 into the crankcase proper. Fumes and blowby gases in the crankcase will be forced outwardly through the ports 48 into the chamber 50 of the manifold structure passing around the flange 86, upwardly through the narrow passages formed by the fins 82 and thence through the somewhat helical passage which is formed by the baffle assembly 70 disposed in the passage 52, then into the chamber 92 of the cover structure 88 and outwardly through the annular port 54 into the low pressure area below the venturi. The fins 82 are, as noted before, formed with large surface areas which act to cause oil which may have been expelled from the crankcase to adhere thereto and/or to drip downwardly and find their way back to the crankcase. The somewhat helical portion of the baffle assemblies 68 and 70 serve also as flame arresters. The crankcase fumes and blowby gases also will, when the fuel spray jet 32 is aspirating, pass upward through the port 58, through the passages formed by baffles 97 and ports 97A into the chamber 60 of the manifold structure, and thence into the passage 62 of the fuel spray jet.

It will thereby be seen that all of the crankcase fumes are exposed to adhesion surfaces for purification before being returned to the intake of the engine cylinder for burning with the fuel-air charge. Also, gums and residue which would otherwise form gummy deposits on working parts of the engine, are effectively trapped in the baffle assembly 70, which can be readily removed, cleaned, and/or replaced.

The various baffles described above which have large adhesion surfaces intended to entrain the residues and also condensed fumes which are expelled from the crankcase are preferably coated with any preferred adhesion improving material, such as a varnish, resin or the like, whereas various working parts of the air intake system such as the throttle valve (not shown) and intake valves

26 are preferably coated with a material to which the solids and oils will not readily adhere, such as Teflon or the like.

Another modification of the invention is shown in FIGURES 8, 9 and 10, respectively similar in most respects to FIGURES 3, 4 and 7, but in which the annular inlet 54 at the throat of the venturi is replaced by a tube 54A extending between the chamber 92 to a point close to one side of the throttle valve 100 when same is moved toward its closed position. The effect of this structure is to decrease the suction applied to the crankcase when the engine is idling, at which time manifold vacuum is at a relatively high value.

In the modification shown in FIGURES 11 and 12, the tube 54A has been replaced by a passage 54B extending through the housing into a boss 54C provided on a cover plate member 30A secured to and closing an opening in a carburetor throttle body 30 adjacent one side of valve 100 which will, when moved towards the closed position, tend to close off the opening from the boss 54C. The plate member 30A is readily removable for cleaning.

The passage 54B connects with the interior of the crankcase structure 12 in this embodiment through a passage 102 leading through the manifold structure 14 and a passage 104 in the crank case structure. A baffle assembly 106 having a threaded plug end 108 is adapted for insertion in the passage 104 so as to be readily removed for cleaning. The baffle assembly 106 serves the same residue-adhering function as the baffle assembly 70 of FIGURE 4.

It will be seen in FIGURES 10, 11 and 12 that the throttle valve 100 has a small orifice opening 108 which registers with the tube 54A or the opening in the boss 54C so that at least some ventilation of the crankcase will occur even if the throttle valve 100 closes completely.

I claim:

1. In an internal combustion engine having a crankcase, engine cylinders, and an air intake manifold connected with said cylinders, an antipollution device for said engine comprising:

- (a) an air intake pipe containing a throttle valve openly connected with said manifold and having a venturi throat,
- (b) structure having a first passage openly connecting said crankcase with said air intake pipe at a point of reduced pressure comprising an opening whose area is varied by the positioning of said throttle valve downstream of said throat to thereby draw crankcase fumes into said pipe, and
- (c) structure having a second passage openly connecting said crankcase with said air intake pipe at a point of relatively high air velocity to thereby force air into said crankcase and purge said crankcase of blowby and other fumes while urging said fumes into said intake manifold.

2. The device as defined in claim 1 and having means in said first passage to collect by adhesion the discharge from said crankcase.

3. The device as defined in claim 2 and comprising baffles disposed in said first passage, said baffles having a coating of material facilitating the adhesion of residue from said fumes on said baffles.

4. The device as defined in claim 1 and in which said first passage has baffles therein in part arranged to separate oil discharge from crankcase fumes and return said oil to said crankcase.

5. The device defined in claim 4 in which said baffles in part form a tortuous path for solid carrying crankcase fumes, and in which said solids are caused to settle, condense or adhere on said baffles.

6. The device as defined in claim 4 and in which said baffles in part form a tortuous passage with a large surface area for adhesion thereon of gums, varnish forming resins, solid particles and residue carried in the fumes.

7. The device as defined in claim 1, including a rocker box housing, a pushrod housing openly connecting said rocker box housing with said crankcase, and means openly connecting said second passage with said rocker box housing to purge said rocker box housing of fumes and ventilate said crankcase.

8. The device as defined in claim 1 and in which said point of reduced pressure comprises an annular opening disposed slightly downstream of said venturi throat.

9. In an internal combustion engine having a crankcase, engine cylinders, and an air intake manifold connected with said cylinders, and antipollution device for said engine comprising

- (a) an air intake pipe containing a throttle openly connected with said manifold and having a venturi throat,
- (b) means forcibly introducing atmospheric air into said crankcase,
- (c) structure having a tubular passage connecting said crankcase with said air intake pipe at a point of reduced pressure formed by the edge of said throttle and the wall of said intake pipe to thereby draw crankcase fumes into said pipe, and
- (d) baffle means in said passage disposed in the path of said fumes.

10. The device as defined in claim 9 and in which said baffle means at least in part comprises structure forming a somewhat helical passageway.

11. The device as defined in claim 9 and in which said baffle means at least in part comprises structure forming a passageway with large wall surface area for adhesion thereon of gums, varnish forming resins, solid particles and residue carried in the fumes.

12. A crankcase ventilation system for an internal combustion engine having a crankcase, engine cylinders, rocker box housings for valve operating mechanism and openly communicating with the crankcase interior through pushrod housings, including air reduction and fuel injection means, an intake manifold, a venturi and a throttle valve downstream thereof, said ventilation system characterized by:

- (a) means inducing air under pressure into said crankcase interior directly and through said rocker box housing,
- (b) means venting crankcase fumes into said air induction means at an area of reduced pressure therein, and comprising an opening in said air induction means at a point immediately above said throttle valve for cooperation therewith to vary the area of said opening by varying the position of said throttle valve and thereby provide a metering means for said crankcase fumes.

13. The system as defined in claim 12 and further characterized by means venting some crankcase fumes into the spray jet of said fuel injection means for aspiration thereof.

14. The system as defined in claim 12 and further characterized by means controlling the reduced pressure acting to vent said crankcase fumes into said air induction means.

15. In combination with an internal combustion engine having a crankcase and an air intake manifold, a carburetor having an inlet port comprising a venturi and a mixing chamber, a throttle disc within said mixing chamber downstream of said venturi, inlet means connecting said mixing chamber with said crankcase for conveying crankcase fumes into said mixing chamber, said inlet means being adapted to cooperate with said throttle disc for varying the area of said inlet means by varying the position of said throttle disc thereby metering said crankcase fumes in accordance with the position of said throttle disc.

16. In the combination defined in claim 15, said inlet means comprising a tube inserted through the wall of said mixing chamber in such position as to be closable by said throttle disc in the maximum closing position of said disc.

17. In the combination defined in claim 15, said throttle disc being provided with an aperture adapted to be in communication with said inlet means in the closed position of said throttle disc to allow for passage of a minimum of crankcase fumes into said mixing chamber when the throttle disc is in its maximum closing position.

18. In combination with an internal combustion engine having a crankcase and an air intake manifold, a carburetor having an inlet port comprising a venturi and a mixing chamber, a throttle disc within said mixing chamber downstream of said venturi, inlet means connecting said mixing chamber with said crankcase for conveying crankcase fumes into said mixing chamber, said inlet means being adapted to cooperate with said throttle disc for metering said crankcase fumes in accordance with the position of said throttle disc, said inlet means comprising a downwardly directed inlet opening within a protrusion extending into said mixing chamber adapted to be closed by said throttle disc in one position of said throttle disc and to be gradually opened in other positions of said throttle disc.

19. In the combination defined in claim 18, said inlet opening being connected to an internal passage within said intake manifold, and a tube in communication with said passage and with said crankcase.

20. The combination defined in claim 19 further characterized in that said crankcase has an opening in communication with said tube provided with baffle means to separate oil discharge from said crankcase fumes.

21. In an internal combustion engine having a crankcase, a cylinder block, a rocker box housing and an air intake manifold provided with a throttle valve, the improvement comprising, passage means connecting said crankcase with said air intake manifold adjacent said

throttle valve, said passage means comprising an air intake pipe associated with said air intake manifold having an opening whose area is varied by the positioning of said throttle valve and connected to said crankcase, and means forcing air under pressure into said crankcase to purge fumes from said crankcase into said air intake pipe through said opening of throttle-varied area.

5 22. The device as defined in claim 21 including as aspirated fuel spray jet arranged for discharging fuel into said intake manifold, and means openly connecting said crankcase with said spray jet thereby to use air and fumes from said crankcase for aspirating said fuel jet.

10 23. The device as defined in claim 22 and in which said last mentioned means comprises structure having a plurality of narrow passages with large wall surface area for adhesion thereon of material carried by said crankcase fumes.
